SETTING TOOL FOR BRIDGING PLUGS

Merida L. Hart, Chickasha, Okla., assignor to
 Lane-Wells Company, Los Angeles, Calif., a
 corporation of Delaware

Application January 10, 1941, Serial No. 373,904

6 Claims. (Cl. 166—1)

My invention relates to setting tools for bridging plugs and among the objects of my invention are:

First, to provide a setting tool which is adapted to be suspended from a conductor cable and electrically operated to cause setting of a bridging plug and thereupon to release from the bridging plug so that the setting tool and cable may be removed;

Second, to provide a setting tool which generates force employed to set the bridging plug by interaction of chemicals, which interaction need not be explosive;

Third, to provide a setting tool operated by the generation of pressure within the tool in which the effect of the hydrostatic head of fluid in which the tool is immersed is minimized and, in any event, applied in a manner tending to assist rather than hinder the operation of the setting tool;

Fourth, to provide a setting tool which may be caused to operate not only a bridging plug but any other well device which is responsive to axial compression, or which requires relative longitudinal movement of its parts;

Fifth, to provide a setting tool which is easily operated and which is inherently adapted to be actuated by remote control without danger of improper operation; and

Sixth, to provide a setting tool which incorporates a piston and cylinder unit, or may incorporate several piston and cylinder units, so that the force generated by the setting tool may be compounded.

With the above and other objects in view, as may appear hereinafter, reference is directed to the accompanying drawing, in which:

Figure 1 is an elevational view of my setting tool shown in conjunction with a bridging plug, the setting tool and bridging plug being in their initial positions assumed when lowered into a well bore;

Figure 2 is a longitudinal sectional view substantially through 2—2 of Figure 1, with the parts in elevation;

Figure 3 is an enlarged sectional view of the power piston substantially through 3—3 of Figure 4;

Figure 4 is a transverse sectional view through 4—4 of Figure 3, showing particularly the chemical cartridges; and

Figure 5 is a top or plan view of the power cylinder substantially from the line 5—5 of Figure 3.

My setting tool is particularly designed for the setting of a bridging plug, designated A in Figure 5;

1. A conventional bridging plug comprises a packing element B, slip and cone means C adapted to coact for the purpose of locking the bridging plug against downward or upward movement in the well casing, or against movement in either direction. To set the bridging plug, one end is drawn upwardly while the other end is forced downwardly so as to compress the bridging plug axially. A mandrel provided with a head D at its lower end carries the packing element and cone means, while a sleeve E fits over the upper end of the mandrel for the application of downward force on the packing element and slip and cone means. The bridging plug may take various forms, but essentially the two ends are moved axially toward each other.

My setting tool includes an adapter shell 1 of tubular form, the lower end of which is adapted to bear against the upper end of the sleeve E, as shown in Figures 1 and 2. Suitably attached to the mandrel, as by a shear pin (not shown), is a setting rod 2 which extends upwardly into the shell 1. The setting rod 2 is attached to a piston rod 3. The piston rod is preferably provided with a bifurcated end 4 adapted to receive a screw 5 which extends laterally through an eyelet formed in the upper end of the setting rod. To permit access, the adapter shell is provided with openings 6.

20 The upper end of the adapter shell 1 is screw-threaded to a partition block 7 and the piston rod 3 extends through the partition block and through a packing gland 8 provided in the partition block.

30 In order to prevent accidental upward movement of the piston rod, a tube 9 extends downwardly from the packing gland 8 around the rod and near its lower end is connected to the rod by a shear pin 10.

35 The upper end of the piston rod 3 is attached to a piston 11 which fits within a cylinder 12 screw-threaded into the upper end of the partition block 7. The piston rod 3 is made as small in diameter as possible so as to minimize the effect of the hydrostatic pressure in which the tool may be immersed, for, in operation of the setting tool, it may be submerged several thousand feet in liquid. However, any hydrostatic pressure tends to urge the piston rod and its piston upwardly, which is a direction in movement to accomplish the setting operation.

Attached to and extending through the piston 11 is a hollow stem 13 which extends upwardly through a second partition block 14 in which is provided a packing gland 15 and is joined to a

cartridge block 16, which is secured to or forms part of a piston 17. A cylinder 18 for the piston is screw-threaded to the partition block 14. Adjacent the cartridge block 16 the hollow stem 13 is provided with a transverse inlet port 19 so that fluid pressure may be transmitted from the upper cylinder through the hollow stem to and out through port 19a below the lower piston 11.

The cartridge block 16 contains a plurality of axially directed cartridge sockets arranged about a common center, each of which receives an explosive cartridge 21. The lower ends of the cartridge sockets are enlarged and internally threaded to receive a chemical container 22. Each chemical container comprises a hollow plug member 23 having a bore therethrough aligning with the explosive cartridge and which, in effect, forms a gun barrel. Attached to the lower end of each plug is a closed cylindrical shell 24 formed of thin, easily ruptured material such as thin sheet copper. Between each plug 23 and explosive cartridge 21 there is secured a shear disc 25 adapted to rupture when the explosive charge is ignited.

The explosive cartridges 21 preferably contain a fuse wire and are adapted to be set off electrically. For this purpose they are provided with contacts 26 at their inner or upper ends, which are engaged by ignition terminals 27. Each ignition terminal is connected to an ignition wire 28 which extends through a small bore continuing from the corresponding cartridge socket. Above each cartridge socket the piston 17 is provided with a recess which receives a terminal socket 29 adapted to coat with the corresponding ignition wire to make electrical contact. The terminal sockets 29 are in turn connected to conductors 30 which extend through the piston 17 and which may be joined electrically by a connector ring 31.

The connector ring is joined to a flexible cable 32 which is coiled in the cylinder 18 above the piston 17 and is joined at its upper end to a terminal block 33. The upper end of the cylinder 18 is threaded for connection to a suitable cable head 34 which in turn is connected to a conductor cable 35.

The partition block 14 is provided with a passage 36 communicating between the cylinder 18 and the exterior of the partition block. Liquid 37 is adapted to be introduced through the passage 36 and is sealed therein by a plug 38. The piston 17 and its cylinder 18, together with the partition block 14, form a power chamber 39, while piston 11, cylinder 12 and partition block 7 form a pressure chamber 40. By reason of the hollow stem 13 and its intake ports 19 the pressure generated in the power chamber 39 is applied equally to pressure chamber 40.

Operation of my setting tool is as follows: The chemical containers 22 are filled with a chemical 41 in liquid or powdered form which, when mixed with the liquid 37, causes a pressure-producing chemical reaction; for example, the liquid 37 may be water and the chemical 41 may be calcium carbide—these react, when mixed, to form acetylene gas.

The setting tool is assembled, as shown in Figure 2, with the pistons in the lower parts of their respective cylinders, in which case the piston rod 3 and setting rod 2 are extended. The setting rod 2 is suitably attached to the bridging plug while the adapter shell 1 rests upon the bridging plug.

The setting tool and plug are then lowered to

the desired position and the cartridges 21 are fired and the explosive pressure thus generated ruptures the thin shells 24, discharging the contents 41 of the shells into the liquid 37 below. In this connection, it should be noted that a comparatively small explosive force is all that is required and the flame from such explosive force is fully extinguished before the acetylene gas can be generated by the reaction of the carbide and water. Upon reaction of the carbide and water, sufficient pressure is generated to shear the pin 10, whereupon both cylinders move upwardly, pulling upon the setting rod 2, while the adapter shell prevents upward movement of the upper end of the bridging plug. If it is desired to effect a downward movement of the upper end of the bridging plug, it is merely necessary to slack off slightly on the cable 35 during the time the setting tool is in the process of operation.

It is preferred to attach the setting rod 2 to the bridging plug by a shear pin (not shown) and to generate sufficient excess pressure that the shear pin is certain to give way, whereupon automatically freeing the setting tool from the bridging plug.

It is preferred to exert several thousand pounds setting pressure on the bridging plug and it has been found by test that such setting force may be easily generated with only a single cylinder. Thus it is not mandatory that there be two pressure chambers; instead the lower pressure chamber and associated parts may be omitted and the piston rod 3 connected directly to the cartridge block.

Inasmuch as it is difficult to insure against absolute seal of the various joints and the packing gland under extreme hydrostatic pressure, means may be provided to equalize the pressures through the piston, should there be a slow development of pressure in the power or pressure chambers 39 or 40. Thus, if well fluid should slowly seep into the power or pressure chambers, small bleeder passages 42 may be provided in the pistons 11 and 17; such bleeder passages are, of course, made small enough to have no appreciable loss of pressure when the chemicals are caused to react.

Various changes and alternate arrangements may be made within the scope of the appended claims, in which it is my intention to claim all novelty inherent in the invention as broadly as the prior art permits.

I claim:

1. A setting tool for well devices, comprising: piston and cylinder means adapted to be connected with a well device; chemicals adapted, when combined, to generate pressure for actuating said piston and cylinder means; a container for initially isolating one chemical from the other; and an explosive means for rupturing said container and forcing said chemicals to mix.

2. A setting tool for well devices, comprising: piston and cylinder units connected in tandem to form compounded pressure chambers; pressure-generating means in communication with both of said pressure chambers, said pressure-generating means including chemicals adapted, when combined, to generate pressure; a container for one of said chemicals initially isolating said chemicals; and an explosive means for rupturing said container and forcing said chemicals to mix.

3. A setting tool for well devices, comprising: a piston and cylinder means adapted to be con-

nected with a well device; a chemical contained in said cylinder; a container for a complementary chemical carried by said piston; and means also carried by said piston for opening said container and permitting mixture of said chemicals in said cylinder, said chemicals adapted to react to generate pressure for moving said piston.

4. A setting tool for well devices, comprising: a piston and cylinder means adapted to be connected with a well device; a chemical contained in said cylinder; a container for a complementary chemical carried by said piston; and an explosive charge also carried by said piston for rupturing said container and forcing the contents thereof into mixture with the first mentioned chemical in said cylinder, said chemicals adapted, when mixed, to generate pressure for actuating said piston.

5. A setting tool for well devices comprising: an expansible pressure chamber containing a chemical; a rupturable container also in said

chamber and containing a second chemical adapted, when mixed with the first chemical, to generate pressure; and an explosive means for rupturing said container and distributing the second chemical intimately in the first chemical.

6. A setting tool for well devices, comprising: a sleeve adapted to bear against one part of said well device; a pull rod secured to another part of said device; piston and cylinder means connected with said sleeve and pull rod and forming an expansible chamber; a chemical in said chamber; a rupturable container also in said chamber and containing a second chemical adapted to react with the first chemical to generate pressure; and an explosive means for rupturing said container and drive said second chemical into intimate contact with the first chemical.
